(57) **CLAIM**

The ornamental design for a camera platform, as shown and described.

DESCRIPTION

FIG. 1 is a front elevational view of a camera platform;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front, top, and left perspective view; and,

FIG. 8 is a rear, bottom, and right perspective view.

The broken lines in the drawings depict environmental subject matter only and form no part of the claimed design.
